UNITED STATES PATENT OFFICE.

ABRAHAM LINCOLN TOWNSEND, OF IOLA, KANSAS.

STOCK-BREEDING APPLIANCE.

1,085,954.

Specification of Letters Patent.

Patented Feb. 3, 1914.

Application filed April 15, 1912. Serial No. 761,377.

To all whom it may concern:

Be it known that I, ABRAHAM L. TOWNSEND, a citizen of the United States, residing at Iola, in the county of Allen and State 5 of Kansas, have invented a new and useful Stock-Breeding Appliance, of which the following is a specification.

The invention relates to improvements in appliances for breeding stock.

10 The object of the present invention is to improve the construction of stock breeding appliances, and to provide a simple, inexpensive and efficient device, designed for taking the pressure off of young sows and 15 other animals, and to prevent them from being crushed or otherwise injured by a heavy boar or other male animal.

With these and other objects in view, the invention consists in the construction and 20 novel combination of parts hereinafter fully described, illustrated in the accompanying drawings, and pointed out in the claims hereto appended; it being understood that various changes in the form, proportion, size 25 and minor details of construction, within the scope of the claims, may be resorted to without departing from the spirit or sacrificing any of the advantages of the invention.

30 In the drawings:—Figure 1 is a perspective view of a stock breeding appliance, constructed in accordance with this invention and shown applied to a sow. Fig. 2 is a central longitudinal sectional view of the 35 same. Fig. 3 is a reverse plan view, the legs or standards being in section. Fig. 4 is a transverse sectional view on the line 4—4 of Fig. 2. Fig. 5 is a transverse sectional view on the line 5—5 of Fig. 2.

40 Like numerals of reference designate corresponding parts in all the figures of the drawings.

In the accompanying drawings in which is illustrated the preferred embodiment of 45 the invention, the breeding appliance comprises in its construction an arched support or rest 1, curved transversely to arch over the back of a sow 2, as illustrated in Fig. 1 of the drawings, and supported by front and 50 rear legs or standards 3, arranged in pairs and inclined laterally to firmly and securely sustain the weight of a heavy animal.

While the appliance is shown in the accompanying drawings as applied to a sow, it 55 is adapted to be advantageously employed in breeding all kinds of stock, and may be con-

structed of any desired size and of any suitable material to meet the conditions or requirements incident to its use. The arched support or rest is composed of two sections 60 4 and 5, constructed of heavy sheet metal or other suitable material and provided at their inner faces with transversely disposed hinge elements 6, adapted to stiffen the sections 4 and 5 and having eyes 7 at their inner ends for the reception of a pintle rod 8, which also passes through aligned eyes 9 of the upper ends of the legs or standards. The hinge elements preferably consist of separate bars or pieces, suitably secured to the sections 4 and 5 and curved to conform to the configuration thereof and tapered outwardly. They are arranged in pairs at the ends of the sections and at suitable points intermediate of the ends thereof, as clearly 75 shown in Fig. 3 of the drawings.

The legs or standards 3, which are constructed of angle iron or other suitable material, are preferably made of metal, as shown, having two wings or flanges arranged at 80 right angles, the eyes 9 being formed in one of the wings or flanges of each leg or standard, and the other wing or flange presenting a smooth surface to the sow or other animal. The upper portions of the legs or standards 85 are curved upwardly and inwardly to conform to the configuration of the transversely curved sections of the support or rest, which fits snugly against and is firmly supported by the legs or standards. The lateral inclination or spreading of the front and rear legs maintains their upper portions in contact with the sections of the support or rest and prevents any movement or play of the parts. The pintle rod 8 is preferably pointed at one end to enable it to be readily passed through the aligned eyes of the sections 4 and 5 and the legs or standards, and it is provided adjacent to its other end with a transverse pin 10 or other suitable means for 100 forming a stop for engaging the adjacent hinge element 6. The pintle rod forms a hinge connection between the sections and also detachably secures the same together and enables the sections with their supporting legs to be readily separated to permit the appliance to be compactly arranged for shipping or storing. The legs are provided 105 at their lower ends with adjustable sections 11, constructed of angle metal and fitting the angularly related flanges or webs of the legs, and adapted to be moved longitudinally

thereof to raise and lower the support or rest and vary the height of the appliance to accommodate animals of different sizes.

In practice, when the appliance is saddled on the animal, as illustrated in Fig. 1 of the drawings, the legs with their extensible sections should be one half of an inch shorter than the legs of the animal so as to just clear the supporting surface when the animal is standing erect. The sections 11 are provided with longitudinal slots 12 for the reception of bolts 13, piercing the legs or standards 3 and equipped with tail nuts 14, located at the inner faces of the legs or standards, as clearly illustrated in Fig. 4 of the drawings. The sections 11 of the rear legs or standards 3 are provided at their lower ends with broad feet 11^a adapted to prevent the rear legs or standards from sinking into the ground in case the same should be more or less soft. These feet 11^a, which may be of any desired construction, are illustrated in the drawings as consisting of flat rectangular plates or pieces, provided with attaching flanges 11^b extending vertically from the upper faces of the plates at the inner rear corners thereof and riveted or otherwise secured to the sections 11. The legs are connected by curved braces 15, arranged in pairs at each side of the appliance and crossed adjacent to the lower outer edges of the sections 4 and 5 and extending downwardly from the upper ends of the legs or standards to about points midway between the ends of the same. The braces 15, which are preferably constructed of flexible or resilient material, are curved or bowed to conform to the configuration of the animal. The support or rest is also braced by curved lugs or arms 16 preferably formed integral with and extending laterally from the upper or inner longitudinal edge of the section 5 and overlapping and fitting against the upper face of the section 4. The lugs or arms 16 limit the relative swinging movement of the sections and assist in preventing the same from collapsing when the appliance is subjected to an excessive weight. While a pair of lugs or arms 16 is shown, any number may, of course, be employed.

The breeding appliance is harnessed to an animal to retain the latter in proper position. The harness, which may be of any preferred construction, is illustrated in the accompanying drawings as comprising a collar 17, a belly band 18 and a rear strap or breeching 19. The collar 17, which is fitted around the neck of the animal, is adjustable by means of a suitable buckle 20, and it is connected at opposite sides with the front legs by straps 21, suitably secured at their terminals to the collar and to the said front legs. One end of the belly band 18 is passed through a slot 22 in the lower portion of the section 4 of the support or rest, and is looped

as shown in Figs. 1 and 5 of the drawings, the terminal portion 23 being riveted or otherwise secured to the body portion of the belly band. The belly band, which passes under the animal and connects the sections 4 and 5, is provided at its other end with a plurality of perforations for engaging a buckled tongue 24, mounted on the section 5 adjacent to a slot 25 through which the free end of the belly band passes. The belly band may, of course, be connected to the sections of the support or rest in any other suitable manner. The rear strap or breeching 19, which is adjustable by means of a buckle 26, passes around the rear portion of the animal and is suitably secured to the rear legs or standards at points intermediate of the ends thereof and approximately in the same plane as the rear ends of the straps 21, which extend downwardly and rearwardly from the collar 17 at a slight inclination. The appliance may be equipped with any other suitable means for securing it to an animal and for retaining the latter in proper position under the appliance.

The support or rest may be of any desired length and it preferably extends from a point adjacent to the neck to within a short distance of the tail of the animal, which is entirely exposed at the rear.

What is claimed is:—

1. A breeding appliance of the class described including a support or rest arranged at an elevation and conforming to the configuration of and adapted to extend over the back of an animal and constituting an exterior support for another animal, and means for confining an animal beneath the rest or support.
2. A breeding appliance of the class described including a rest arranged to extend over the back of an animal and forming an exterior support for an animal, legs supporting the rest and spaced apart to permit an animal to be arranged beneath them, and means for confining an animal beneath the rest.
3. A breeding appliance of the class described including an arched support or rest arranged at an elevation and adapted to fit over or saddle the back of an animal and forming an exterior support for an animal, and means for confining an animal beneath the support or rest.
4. A breeding appliance of the class described including an arched support arranged to fit over the back of an animal and forming an exterior support for another animal, and legs or standards connected with the support at opposite sides thereof and spaced apart to receive an animal between them.
5. A breeding appliance of the class described including an arched support arranged to fit over the back of an animal

and forming an exterior support for another animal, legs or standards connected with the support at opposite sides thereof and spaced apart to receive an animal between them, 5 and a harness for securing the appliance on an animal and for retaining the latter in proper position under the appliance.

6. A breeding appliance of the class described including an arched rest adapted to 10 saddle or fit over the back of an animal and forming an exterior support for another animal, means located at opposite sides of the appliance and supporting the said rest and spaced apart to permit the arched rest 15 to be placed over the back of an animal, a collar having flexible means for connecting it with the front of an animal, a rear or breeching strap extending around the back of the appliance, and a belly band connected with the arched support and adapted 20 to extend under an animal.

7. A breeding appliance of the class described including a rest adapted to be arranged over the back of an animal and 25 forming an exterior support for another animal and composed of separate sections hinged together, and supporting means connected with the sections.

8. A breeding appliance of the class described including a rest adapted to extend 30 over the back of an animal and forming an exterior support for another animal and divided longitudinally into two sections, which are hinged together, supporting 35 means connected with the outer portions of the sections, and an arm extending from one of the sections and overlapping the other to limit the relative movement thereof.

9. A breeding appliance of the class described including a rest adapted to extend 40 over the back of an animal and forming an exterior support for another animal and composed of two longitudinal sections having supporting legs and provided with 45 eyes, and a longitudinal pintle passing through the eyes and hinging the sections together.

10. A breeding appliance of the class described including a transversely curved or 50 arched rest adapted to extend over the back of an animal and forming an exterior support for another animal and composed of two longitudinal sections, legs having curved upper portions supporting the sections and

provided with eyes, and means passing 55 through the eyes of the legs for hinging the sections together.

11. A breeding appliance of the class described including a support arranged to fit over the back of an animal and constituting 60 an exterior support for another animal composed of transversely curved sections provided at their lower faces with hinge elements, legs having curved upper portions secured to the lower faces of the said sections and provided with eyes, and a pintle rod passing through the hinge elements and the eyes of the said legs. 65

12. A breeding appliance of the class described including a rest adapted to be arranged over the back of an animal and 70 forming an exterior support for another animal, spaced legs supporting the rest, and flexible means secured to the legs for confining an animal beneath the rest. 75

13. A breeding appliance of the class described including a rest adapted to be arranged over the back of an animal and forming an exterior support for another animal, legs supporting the rest and having 80 adjustable sections for varying their length, and means for securing the apparatus to an animal.

14. A breeding appliance of the class described including an arched rest adapted to 85 be arranged over the back of an animal and forming an exterior support for another animal, legs having curved upper portions secured to the said rest, and braces connecting the legs and curved to conform to the 90 configuration of an animal.

15. A breeding appliance including a rest or support arranged at an elevation and adapted to extend over the back of an animal and forming an exterior support for 95 another animal, and front and rear legs or standards supporting the rest, the rear legs or standards being provided with relatively broad feet adapted to prevent the said rear legs or standards from sinking into the 100 ground.

In testimony, that I claim the foregoing as my own, I have hereto affixed my signature in the presence of two witnesses.
